UNITED STATES PATENT OFFICE.

ABRAM WALRATH, OF WEEDSPORT, NEW YORK.

SILO.

No. 820,750.

Specification of Letters Patent.

Patented May 15, 1906.

Application filed October 12, 1903. Serial No. 176,633.

To all whom it may concern:

Be it known that I, ABRAM WALRATH, a citizen of the United States, and a resident of Weedsport, in the county of Cayuga, in the State of New York, have invented new and useful Improvements in Silos, of which the following, taken in connection with the accompanying drawings, is a full, clear, and exact description.

This invention relates to the class of silos which are provided with a vertically-extended or continuous doorway and a series of doors for closing the said doorway.

The invention consists in an improved construction of the silo-doors and means for closing the same, as hereinafter described, and set forth in the claims.

In the accompanying drawings, Figure 1 is a front elevation of a silo equipped with my improved doors. Fig. 2 is an enlarged horizontal transverse section on the line X X in Fig. 1. Fig. 3 is a further enlarged vertical sectional view on the line Z Z in Fig. 2. Fig. 4 is a similar view on the line Y Y in Fig. 2. Fig. 5 is a detached isometric perspective view of the lowermost door minus its clamping device, and Fig. 6 is a vertical transverse section on the line U U in Fig. 5.

Similar letters of reference indicate corresponding parts.

A represents the body of the silo, formed of staves united by tongue-and-groove joints and bound by hoops *a a* in the usual manner. The front of this silo is formed with a continuous or vertically-extended opening or doorway *b* between posts *c c*, extending from bottom to top of the body A, as shown in Fig. 1 of the drawings.

d d d represent a series of doors which are seated directly one upon the other and are sustained in the doorway *b* by my improved construction of said parts and by the novel means of clamping the doors in their closed position, which improvements possess important advantages and constitute the salient features of my invention, which I shall now describe.

The door-post *c* at one side of the doorway *b* is formed with a vertically-grooved jamb *e*. The groove is preferably made V-shaped for wedging therein one of the side edges of the doors *d*, as shown in Fig. 2 of the drawings, in which case the said edge of the door *d* is double-beveled or V-shaped, as shown at *e'*, corresponding to the V-shaped jamb *e*. Aside from the said wedging action the groove of

the jamb *e* with the edge of the door seated therein serves to prevent inward as well as outward falling of the door in placing it in the doorway *b*. The other door-post *c'* is formed with a jamb *f*, which is beveled uniformly inward from the exterior to the interior of the silo, and the adjacent side edge of the door is beveled outward, as shown at *f'*, to conform to said jamb.

In the operation of closing the door *d* it is first inserted with its V-shaped edge into the groove of the jamb *e*, in which the door can be swung from the interior of the silo outward to place the edge *f'* of the door onto the beveled jamb *f*.

By means of a suitable clamping device *g*, connected to the door *d*, adjacent to the beveled edge *f'* thereof and engaging the exterior of the door-post *c'*, the said door is forced outward and onto the beveled jamb *f*, which causes the door to be pushed sideways and wedge the edge *e'* thereof into the groove *e* of the jamb on the post *c*. The door is thus thoroughly wedged on the two jams.

I preferably form the clamping device *g* of a lever which is pivotally connected to a tubular stud *h*, projecting from a plate *h'*, firmly secured to the exterior of the door adjacent to the beveled edge *f'* thereof. A bolt *i*, passing through the clamp-lever *g* and through the stud *h* and door *d* and provided with a head engaging the inner side of the door, serves as a pivot to the said clamp-lever, which is retained on the stud *h* by means of a nut on the outer end of the bolt *i*.

The portion of the clamp-lever *g* which engages the exterior of the post *c'* is beveled to form an upwardly-disposed wedge *j*, as shown in Figs. 2, 3, and 4 of the drawings, so that a downward pressure applied to the cam-lever causes the wedge *j* to press with increasing force onto the exterior of the post *c'*, and thus draw the door with a correspondingly-increased force onto the beveled jamb *f*, which contact causes the door to be forced laterally into the grooved jamb *e*, and thus the closed door is perfectly tightened in both of the vertical jambs. Simultaneously with this effect of the cam-lever the door receives a downward pressure, so as to be tightly seated on the subjacent door.

This last-mentioned effect is produced by the downward pressure applied to the cam-lever *g* in the operation of closing the door.

To obviate wear and abrasion of the post

c' by the engagement of the cam-lever, I attach to the exterior of said post a bar of angle-iron *l*, as shown in Figs. 1 and 2 of the drawings.

5. To enable the side edges of the door *d* to better resist the pressure of the jambs, I form the said door of a tier of staves matched together, as shown in Figs. 5 and 6 of the drawings, and tied together by means of dowels 10 *n n*, passing through the staves. The door is thus formed with smooth surfaces and prevented from warping and splitting.

15 *o o* denote spreader bars or rods which extend across the doorway at the exterior of the silo-body *A* and pass with their ends through the posts *c c'* and are provided with nuts *o' o'*, engaging opposite sides of each post to adjustably tie said posts to each other and hold them firmly in place.

20. In filling the silo the doors *d d* are placed successively one upon the top of the other and wedged onto the jambs *e* and *f* by tightening the clamp-levers *g g* on the post *c'*. In removing the silage the uppermost door or 25 doors are taken out of the doorway *b*, and then as the bulk of silage becomes reduced the remaining doors are consecutively loosened by turning the clamp-levers and pushed up in the doorway sufficiently to make the 30 necessary opening for removal of the silage. By reclamping the raised doors said doors are retained in their elevated position. After the silo is emptied the clamp-levers of the elevated doors are loosened sufficiently to allow said doors to drop to their normal position in the doorway and may be clamped preparatory to refilling the silo. It will thus be observed that the doors *d d* are always in a 35 convenient position for closing the doorway, and the tightening of the closed doors is 40 quickly and effectually accomplished.

What I claim as my invention is—

1. A silo having a vertically-extended opening forming a doorway, a door-post formed in its jamb or inner face with a vertical groove V shape in cross-section, and an opposite door-post having the jamb or inner face beveled inwardly of the silo, a series of doors disposed successively one upon the top 45

of the other and in the same vertical plane, 50 each of said doors being movable vertically and laterally in the opening and having their edges conformed to the aforesaid jambs, and means for locking the edge of the doors separately in its closed position, and during the 55 locking operation for causing said doors to be moved laterally and downwardly in the opening to wedge the same with the jambs of the door-posts.

2. A silo having a vertically-extended 60 opening forming a doorway, a door-post formed with a vertically-grooved jamb, and an opposite door-post formed with an inwardly-beveled jamb, a series of doors disposed successively one on top of the other in 65 the same vertical plane, and each movable independently vertically and laterally in the opening, said doors having their edges conformed to the aforesaid jambs to fit therewith, and means movably connected to each 70 door to engage the exterior of the door-post formed with the beveled jamb and lock the doors, said means acting to move the doors laterally and downwardly during the locking operation, substantially as described. 75

3. In a silo provided with a vertical door-opening, the combination of a door-post having a vertically-grooved jamb, and an opposite door-post having an inwardly-beveled jamb, and a door having its edges conformed 80 to said jambs to fit therewith, and means for forcing the door to its closed position and simultaneously with said closing of the door to move the same laterally toward the grooved jamb and downwardly, substantially as described. 85

4. A silo having a vertical opening forming a doorway, door-posts, one of which is grooved, the other beveled, doors fitting said door-posts and clamps carried by the doors 90 and adapted to draw the doors between the door-posts and move the doors downwardly in the opening.

ABRAM WALRATH. [L. s.]
